UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,837**, dated September 2, 1873; application filed August 9, 1873.
[Term of Patent 3½ years.]

L.

To all whom it may concern:

Be it known that I, FREDERICK WINK, of Philadelphia, Pennsylvania, have invented a Design for a Shawl-Pattern, of which the following is a specification:

My design for a shawl-pattern is fully illustrated by the figure in the accompanying drawing, and consists of alternate wide and narrow stripes, A and B, upon a plain ground, D. The central member *a* of the stripe A is elaborately ornamented by arrow-heads, ribbed borders, dots, and short transverse and longitudinal ribs, the whole being arranged in a manner so clearly shown in the drawing as to require no minute description. The said stripe A is further ornamented by parallel ribs of different widths and shades or colors, and by rows of dashes, as shown. The stripe B is com-

posed of a series of parallel ribs, some strongly contrasted and others blended into each other, there being also upon these ribs longitudinal rows of dashes, all arranged in the manner clearly represented in the drawing.

Irrespective of the colors employed, I claim—

1. The design for the stripe A, as described and represented.
2. The design for the whole pattern, including the stripes A and B.

In testimony whereof I have signed my name to this specification in the presence of two subscribing witnesses.

FRED. WINK.
